UNITED STATES PATENT OFFICE.

FRANK VINCENT WHYLAND, OF SALISBURY, CONNECTICUT, ASSIGNOR TO
GEORGE B. BURRALL, OF LAKEVILLE, NEW YORK.

SWAGING-MACHINE.

SPECIFICATION forming part of Letters Patent No. 629,838, dated August 1, 1899.

Application filed February 3, 1899. Serial No. 704,368. (No model.)

To all whom it may concern:

Be it known that I, FRANK VINCENT WHYLAND, a citizen of the United States, residing at Salisbury, in the county of Litchfield and State of Connecticut, have invented certain new and useful Improvements in Swaging-Machines, of which the following is a specification, reference being had to the accompanying drawings, in which—

10 Figure 1 is a side view of my machine. Fig. 2 is a vertical central lengthwise section of the machine. Fig. 3 is a vertical cross-section of the swaging-head on line 33 of Fig. 2. Fig. 4 is a vertical cross-section taken through the line 44 of Fig. 2. Fig. 5 is an elevation partly in section and shows the stop-motion. Fig. 6 is a view, partly in cross-section, of the casting B and the fingers b. Fig. 7 is a top plan view of the machine. Fig. 8 is a plan view of spoke-wire W, showing blanks and swaged portion. Fig. 9 shows cross-section of the roller-bushing b². Fig. 10 shows roller b³.

15 Like letters refer to like parts throughout the several views.

20 In the drawings illustrating the principle of my invention and the best mode now known to me of applying that principle (see Figs. 1 and 2) the standard A supports the casting B, which is the outer casing of the swaging device and is firmly held to the support A by the cap A' and the bolts a a and nuts a' a' or in any other suitable manner. The standards and frame A³ support the working parts of the feeding and shearing devices described

25 below.

G is a driving-pulley splined at g on the hub g' of the fly-wheel G', and G² is a loose pulley on the same hub g'. The fly-wheel G', through its hub g', is fast on head-shaft H, through the center of which and for its entire length is drilled a wire-passage h of suitable diameter to allow the passage of the wire to be operated upon. The inner end of the wire-passage h is preferably contracted to 40 the diameter of the wire W in order to guide it properly to the swaging-dies J².

B' is a steel band shrunk on the inner end of casing B over the fingers b to increase the resistance of fingers b to the force of the hammering and swaging blows and to reinforce the blocks b'.

The stationary head or casing B, containing the swaging device, is constructed as follows, (see Fig. 3.) The inner ends of casing B is formed with a plurality of fingers b, in 55 the spaces between which are mounted reinforcing-blocks b', (of hardened steel,) which rest on cylindrical bushings b², (of hardened steel,) which are formed with lengthwise openings in their inner faces. These bushings b² 60 contain rollers b³, (of hardened steel,) which project into the central chamber b⁴ of the casing B. (See Fig. 3.) Head-shaft H (see Fig. 2) projects into said chamber b⁴ and is provided at its inner end with a boss h', grooved 65 at h³ across its inner face, the opposite sides of the groove being equidistant from the middle of the boss h' and coincident with the lengthwise axis of head-shaft H. The boss h' is recessed at the middle of its front face to 70 receive the bushing h², which is set loosely in an annular opening therein provided. The hammers J, the wedges J', and the swaging-dies J² are loosely mounted in grooves h³ of the boss h', the hammers J and dies J² being 75 actuated by the successive contact of the cam-shaped ends j of the hammers J with the inwardly-projecting peripheries of the rollers b³. The wedges J' are actuated by mechanism 80 hereinafter described.

The reinforcing-blocks b', the bushing b², the rollers b³, the hammers J, the wedges J', the swaging-dies J², and the head-shaft bushing h² are all subject to rapid wear and require to be replaced with more or less frequency. 85 To facilitate the substitution of worn parts, the elements just above mentioned are removable and are retained in their respective positions by concentric face-plates b⁵ and b⁶, plate b⁵ being removably fixed to head B and plate b⁶ being removably fixed to the collar or boss h' and rotating therewith and having suitable holes or slots b⁹ for the reciprocation therethrough of the wedges J'.

To regulate the force of the blows delivered by the hammers J upon the dies J², I provide tapered wedges J', inserted between the hammers J and the dies J², pivotally connected with the grooved revoluble collar K, which has backward and forward motion upon the collar-stud K', the said stud K' being a part of the frame A³ and operatively con-

ected on the frame with relation to the rotating boss h' . The collar K is actuated by the lever K^2 , which is pivotally connected at k with the cam-lever K^3 . The cam-lever K^3 is fulcrummed at k' on collar-stud K' . The cam-lever K^3 is provided with a cam-roller k^2 , which works with the cam K^4 . The wedges J' are forced inwardly between the hammers J and the swaging-dies J^2 by the movement 5 of the collar or wedge-carrier K toward the boss h' , this movement being due to the push of cam K^4 on the cam-roll k^2 . When the portion k^3 of cam K^4 is against the cam-roll k^2 , the spring K^5 serves to pull the wedge-carrier 10 K and wedges J' outwardly from their most effective wedging position, so that the cam-shaped ends j of the hammers J are out of working contact with the rollers b^3 . One end of spring K^5 is fast to frame A^3 and the other 15 end to cam-lever K^3 , and the spring is distended when the inward movement of the wedge-carrier occurs.

Cam-lever K^3 is provided with a suitable device K^6 (conveniently a turnbuckle) to increase or decrease its length, so that a proper 20 adjustment is secured for the insertion or withdrawal of the wedges J' between the hammers J and the dies J^2 . The cam K^4 and a cam K^7 and a worm-gear K^8 are each supported 25 on shaft K^9 , which is actuated through the worm K^{10} , (see Fig. 8,) the shaft K^{11} , which carries the worm K^{10} , passing through suitable bearings in the frame A^3 and the standard A and being provided with suitable driving-pulleys K^{12} and K^{13} . These pulleys are of 30 different diameters to secure different speeds for shaft K^{16} and are each mounted on a hub K^{14} , loose on the shaft K^{11} , which is adapted to be coupled to the hub K^{15} , which is fast on 35 shaft K^{11} .

Cam-shaft K^9 (see Figs. 2, 4, and 5) carries a rocker-arm K^{16} , which has a lengthwise slot k^4 , in which there is an adjusting-block k^5 , which is adjusted in its slot by the adjusting-screw L. This block k^5 is pivotally connected 45 by a pin l with a slide-block L', mounted in the lengthwise slot l' of the rocker-lever L^2 , which is pivoted at l^2 to the base of the machine. The upper end of rocker-lever L^2 50 is loosely jointed at l^3 with the connecting-rod L^3 for carriage D'. That end of the rocker-lever L^2 with which the connecting-rod L^3 is thus connected is furnished with a lengthwise opening l^4 , in which a spring l^5 is 55 mounted rearwardly of the pin l^6 . The other end of the connecting-rod L^3 is adjustably connected to the carriage by means of the clamp-bolt l^6 through the elongated slot l^7 . By this adjustment the position of the carriage 60 in relation to the wire is regulated independently of the adjustment of the slide-block L'. Rocker-lever L^2 is provided with an abutment l^8 , which on the back stroke of the rocker-lever L^2 strikes slide-bar L^4 , carrying 65 an inclined shoe l^9 , which co-operates with the inclined block l^{10} in the vertical

slide-bar l^{11} and serves to pull the slide-bar l^{11} downwardly against the stress of a spring l^{12} , mounted above the horizontal abutment l^{13} , through which the slide bar or rod l^{11} passes, 70 the rod being provided with a fixed collar l^{14} to engage the upper end of the spring l^{12} . The upper end of the slide-rod l^{11} extends into the path of an abutment l^{15} on the bottom of the carriage D'. On the back stroke 75 of the carriage the pin l^8 engages the spring l^9 in the outer end of the connecting-rod L^3 and compresses it slightly. As this spring is compressed the shoe l^9 moves the slide-rod l^{11} downwardly and out of the path of abutment l^{15} , so that the carriage D' moves again and carries the wire which has been operated on and is still clamped by the jaws D² D³ (on carriage D') a distance equal to that portion of the spoke which is called the "blank." 80 The carriage on its back stroke is first brought to rest by engagement of abutment l^{15} with the upper end of the slide-rod l^{11} . It is at this time that the wire ceases to move lengthwise and that the swaging-dies J^2 form the shoulder x' , (see Figs. 2 and 8,) the swaging-dies J^2 acting during the interval that the wire is at rest to form a nicely-finished shoulder x' instead of a more or less imperfectly-formed shoulder, as would happen if the wire 85 were moved continuously. The interval required for compressing the spring l^9 and pulling the slide-bar l^{11} out of the path of abutment l^{15} practically corresponds to the interval required to form the shoulder x' , and 90 when the shoulder x' is completed the carriage moves on to its outermost limit, the extent of this movement corresponding to the length of the blank.

The jaws D² D³ are loosely pinned at their 95 butt-ends to the upright d of carriage D', the free end of one jaw facing the free end of the other jaw and both jaws pointing toward the swaging mechanism. The range of movement of one of the jaws is limited by a stop d^4 , 100 mounted in a bracket d^2 of the carriage D'. The other jaw, which is opposite its mate, is moved toward the wire to clamp it by the cam d^5 on the end of rod d^4 , which carries a roll d^6 , that runs in the lengthwise raceway d^8 of 105 the vertically-movable frame d^7 . This frame d^7 is guided in vertical ways d^8 d^9 in the frame A³. Frame d^7 is provided with a dependent cam-roll d^{10} , which works with the cam K⁷. When the cam K⁷ is in operative position, the 110 frame d^7 is at its lowest position, falling downward in its ways by gravity, and the under jaw D² then gravitating away from the wire W. When the swell of the cam K⁷ rises against and past cam-roll d^{10} , frame d^7 is lifted, carrying the under jaw D² against the wire W 115 and clamping it against the upper jaw D³. The dependent cam-roll d^{10} is adjustable on the frame d^7 in order to suit wires of different diameters, the adjusting-screw d^4 serving, 120 with the adjustable cam-roll d^{10} , to regulate the jaws to wires of different diameters and 125 130

also to so adjust the jaws that their working ends are operative on work kept central in relation to the swaging mechanism.

To secure any desired length of blank in a given length of spoke, carriage D' is formed with a lengthwise slot d¹¹, and the upright d, to which the jaws D² D³ are pivoted, is provided with a horizontal side plate d¹², through which a clamp-bolt d¹³ passes into and through the slot d¹¹. Carriage D' is provided with a horizontal slide-plate f, having a lengthwise slot f', through which a clamping-screw f² extends to lock the plate in adjusted position on the carriage. This plate f carries an upright f³, in which is mounted the wire-guide f', this guide having a hole through it for the passage of the wire W. One of its functions is that of a shear-blade. The movable member f⁵ of the shearing mechanism is a vertically-reciprocating bar having a hole through it for passage of the wire, and when the movable member slides upwardly, the wire being through the hole in guide f' and also through hole in member f⁵, the wire is cut off, as will be readily understood. Cutting member f⁵ is actuated by the rocker-lever f⁶, fulcrumed on a stud f⁷ on the carriage D'. One arm of the rocker-lever f⁶ works in a hole in the movable cutting member f⁵, and its outer end is provided with a roller f⁸, which runs in the raceway d⁸ of the vertically-movable frame d⁷. The up-and-down motions of this frame d⁷ effect the requisite reciprocations of the movable cutting member f⁵.

Carriage D' is movable lengthwise of the machine toward and away from the swaging mechanism and is mounted on ways d¹⁸ in frame A³.

Considering the mechanism in the position shown in the drawings, a spoke is supposed to have been just severed at the middle of a blank-section of the wire, the movable cutting member f⁵ is just returned to its position of rest, and the jaws D² D³ released from the wire, so that the carriage is free to carry the jaws and the severing mechanism toward the swaging mechanism, through which it is supposed the second of two continuous blank-sections has just been drawn. These two continuous blank-sections are marked x³ and x⁴ in Fig. 2. The carriage now moves back toward the swaging-head and the wedges enter inwardly between the hammers and dies to the full extent provided and, the jaws pass over the wire, which passes outward through the coincident holes in the wire-guide f' and the hole in the movable cutting member f⁵. When the carriage reaches the limit of its inward movement, jaws D² D³ seize at or nearly on the swaged portion of the wire and at the same instant the shearing device is actuated and severs the spoke just pulled through by the feeding device, and the carriage now moves back with the wire, which is being constantly hammered or swaged as it is pulled through the swaging mechanism, until the

abutment l¹⁵ strikes the stop or slide rod l¹¹. Then, as above described, the carriage takes a fresh start rearwardly and the swaging-dies 70 stop work, allowing the formation of two continuous blanks. The jaws are again opened, and the carriage moves inwardly to grasp and pull another spoke.

The main advantages of the herein-described machine are the simplicity of the construction of the swaging-head, permitting quick and easy renewal of worn parts and the momentary stopping of the carriage while the second shoulder is being formed and the 80 subsequent completion of the back stroke of the carriage at the same rate of speed that it had at the first part of its rearward movement. Heretofore the final movement of the carriage has been accelerated just before the 85 second shoulder was finished, with the result that the wire was carried too swiftly to permit proper swaging of the spoke about an inch in front of the second shoulder, this part of the spokes heretofore swaged being characterized by a rough or ridge-like conformation, deemed highly objectionable by those skilled in the art.

What I claim is—

1. In a swaging-machine, the combination 95 with a casing having a plurality of fingers, of reinforcing-blocks and of bushings bound together by a reinforcing-band; rollers contained within said bushings; a boss formed with a groove; a hollow shaft rotating within said casing and carrying said boss; hammers sliding in the outer part of said groove; swaging-dies sliding in the inner part of said groove; wedges entering said groove between said hammers and said dies; a wedge-carrier; 105 a shaft for said carrier; a slide controlling said carrier; a lever for operating the slide; a cam controlling said lever; and means to rotate said cam.

2. In a swaging-machine, the combination 110 of a supporting-frame; swaging mechanism; coacting jaws; a jaw-carrying carriage; mechanism for reciprocating said carriage; mechanism for temporarily arresting said carriage at an intermediate point in its travel while 115 said swaging mechanism is in operation; and mechanism for releasing the carriage from said arresting means and completing the movement of said carriage in the same direction from said intermediate point to the end 120 of its travel.

3. In a swaging mechanism, the combination of a main stationary frame, a carriage sliding in said frame; a rocker-arm; a rocker-arm shaft; means to rotate said shaft; a 125 rocker-lever; a slide-block; means to adjust said slide-block; a link connecting said carriage and said rocker-lever; a spring interposed between said rocker-lever and said link; a lug on said rocker-lever; a slide-bar in the 130 path of said lug; a shoe fast on said slide-bar; a slide-rod formed with a beveled foot arranged to be engaged by said shoe; a spring controlling said slide-rod; and an abutment

on said carriage arranged to strike said slide-rod when the latter is extended.

4. In a swaging-machine, the combination with a swaging mechanism comprising a casing; a rotary head within said casing; a plurality of endwise - reciprocating hammers mounted in said rotary head; and a plurality of endwise-reciprocating dies mounted in said rotary head; and means for actuating said hammers; of a reciprocating wedging mechanism comprising a stud-shaft situated upon the frame in front of the casing; a revoluble collar carried thereby; wedges mounted operatively upon said collar; and a mechanism 15 for reciprocating the revoluble collar to enter the wedges between opposed ends of the hammers and dies from the front of the casing.

5. In a swaging-machine, a swaging mechanism comprising a casing and a grooved boss, 20 one being stationary and the other rotary; means within said casing for moving contained hammers endwise; a plurality of hammers mounted and sliding endwise in the

groove in said boss; a plurality of swaging dies mounted and sliding endwise in said 25 groove; an aperturad face-plate fast to said boss; a plurality of endwise-movable wedges, each of which operates between the opposed inner ends of the hammers and swaging-dies; a stud-shaft situated upon the frame in front 30 of said casing; a revoluble collar carried thereby; said wedges being mounted operatively upon said collar; means for reciprocating said revoluble collar to reciprocate the wedges through said apertures in the face- 35 plate, and between opposed ends of the hammers and dies.

In testimony whereof I have signed my name to this specification, in the presence of two subscribing witnesses, on this 13th day 40 of December, A. D. 1898.

FRANK VINCENT WHYLAND.
